UNITED STATES PATENT OFFICE.

FRANK BOGGS, OF ATLANTA, NEW YORK.

DOUBLE-BELT POTATO-SORTER.

1,136,584.

Specification of Letters Patent. Patented Apr. 20, 1915.

Application filed December 23, 1913. Serial No. 808,464.

To all whom it may concern:

Be it known that I, FRANK BOGGS, a citizen of the United States, residing at Atlanta, in the county of Steuben, State of New York, have invented certain new and useful Improvements in Double-Belt Potato-Sorters; and I do hereby declare the following to be a full, clear, and exact description of the invention, such as will enable others skilled in the art to which it appertains to make and use the same.

This invention relates to sorting apparatus and more particularly to fruit and vegetable sorters, and has for its object to provide a sorter including a series of separating belts, one within the other, to effect the separation of several different sizes of potatoes or other vegetables.

Another object is to provide means for delivering the sorted vegetables from the machine in an efficient manner.

Another object is to provide means for moving the belts which will include drums so constructed as to be adjustable for different belts and also so made as to facilitate repairs.

Another object is to provide guide rolls to promote the ease of operation of the device and also to provide an improved belt for use in conjunction with such rolls.

Another object is to provide means for varying the tension of the belts.

In the drawings: Figure 1 is a side elevation of the complete machine. Fig. 2 is a top plan with the belt removed. Fig. 3 is a vertical sectional view taken centrally and longitudinally through the machine shown in Fig. 2. Fig. 4 is an end view. Fig. 5 is a transverse section on line 5—5 of Fig. 3. Fig. 6 is a fragmentary perspective view of the belt. Fig. 7 is a perspective view of the angular driving drum. Fig. 8 is a detail showing one of the guide rolls and its mounting.

Referring now to the drawings, the present invention comprises a frame including side walls 9 and 10 between which, at one end, there is mounted an angular driving drum of peculiar construction to be later described, the drum being indicated at 11. At the opposite end of the side walls a cylindrical drum 12 is mounted therebetween and between the two drums there are a plurality of transverse angular supporting rolls 13, pivotally mounted.

The frame is supported by forward legs 14 adjacent to the drum 11 and by rearward legs 15 adjacent to the drum 12.

A hopper 16 is mounted upon the side walls 9 and 10 at the rearward end of the machine and just forward of the drum 12.

Forwardly of the legs 15 there are a pair of supplemental legs 17, opposite each other transversely of the machine and between these supplemental legs there is pivoted a transverse tension roller 18, arranged for adjustment vertically of the supplemental legs.

Engaged around the drums 11 and 12 and beneath the drum 18 there is a separating belt 19 of the structure disclosed in my issued Patent No. 1,032,375, but including a modification to be later described. This belt rests upon the rolls 13 which, being angular, agitate the belt as it passes thereover.

As set forth in the issued patent referred to, the belt is composed of a plurality of interwoven pieces of wire, each formed into loops 20 having parallel arms 21, the arms of the adjacent loops being connected by small vertical loops 22, the arms of the adjacent loops lying one above the other. In the complete belt the small loops 22 of one of the pieces of wire are engaged centrally of the large loops of the adjacent piece of wire, there being thus formed a plurality of substantially shield-shaped openings through the belt, and the structure resulting in a plurality of transverse pivotally connected sections A. The modification of the original structure of the belt, referred to above, lies in the treatment of the free ends of the wires at the sides of the belt. In the present structure one free end of each section terminates in one of the small loops 22, as in the original issued patent, but the opposite free end is carried through the small loop 22 in which it is engaged, as shown at 23 and is then carried away from this loop, rearwardly, to a point adjacent the terminal large loop 20 of the next section, where it is bent inwardly toward the center of the belt as shown at 24.

To prevent any drag interfering with the movement of the belt around the drums and rolls, incident to engagement of the edges of the belt with the sides of the machine, there are provided guide rollers 26, these rollers being mounted in openings 27 formed in the side walls 9 and 10, these guide rolls being mounted upon vertical pivots 28 which are

- secured at their lower ends to straps 29 pivoted for horizontal movement upon blocks 30 secured against the outer faces of the side walls adjacent to the openings 27, the 5 pivoting of the straps 29 being accomplished through the medium of bolts 31 engaged through the blocks 30 and passed through openings 32 in the straps, above which suitable nuts 33 are engaged with the bolts so 10 that the straps may be held at different points of their pivotal movement. This permits of movement of the guide rolls 26 toward and away from the edges of the belt and it will be observed that the structure of 15 the belt, which includes the modification above set forth makes it possible to employ these guide rolls, when such use would be impossible if the edges of the belt did not present substantially unbroken lines.
- 20 A guide roll 34, similar to the rolls 26 and correspondingly mounted is connected with each of the rearward legs 15 to engage the edges of the upwardly extending portion of the belt between the drum 12 and the tension roller 18.

Wholly within the inclosure of the belt 19 there is a similarly made belt 35 but of smaller mesh, and this belt is mounted on a rearward circular drum 36 mounted between 30 the side walls below the drum 12 and also upon a second angular driving drum 37 located below and rearwardly of the driving drum 11. This second belt 35 is supported by transverse angular rolls 38 mounted between 35 the side walls and it also extends around a second tensioning roll 39 mounted for vertical adjustment between the legs 17 above the roll 18.

Secured between the walls 9 and 10 forwardly of the drum 37 there is a chute 40 leading out at the side of the machine below one of the side walls, this chute being adapted to receive from the forward end of the belt 35 where it passes over the drum 37. 45 A second chute 41 is mounted between the side walls beneath the upper portion of the belt 35 at the rearward end thereof, and a suitable apron 42 extends from the forward edge of this chute 41 to a cross bar 43 which 50 is mounted between the side walls 9 and 10 just rearwardly of the drum 37.

A crank is provided for the rotation of the drum 11 and suitable driving connections extend between this drum and the drum 55 37 for movement of the two drums simultaneously in the same direction.

The two drums 11 and 37 each consist of an angular core 44 having secured to each of its faces a slat 45 which projects beyond the 60 next face, and these slats are adjustable to project different distances beyond the faces of the core so as to adjust the space between the free edges of the adjacent slats, as will be understood, to correspond to belts having 65 sections A of different widths. The slats

may also be reversed, being detachable as illustrated so as to present a new edge to the belt when they have become abraded.

In operation, vegetables to be sorted are fed into the hopper 16, falling upon the upper portion of the belt 19. The drum 11 is rotated to move the upper portion of the belt forwardly, when the smaller vegetables will pass through the belt, falling upon the second belt 35 and the larger vegetables will 75 pass from the forward end of the machine into a suitable receptacle. The larger vegetables upon the belt 35 will be discharged therefrom into the chute 40 and the smaller vegetables will pass through this belt and 80 will be discharged from the chute 41.

Guide rolls 46 are provided for the edges of the second belt 35 and are mounted similarly to the rolls 26, and it will be observed that the upwardly extending portions of 85 both belts are close together so as to be guided by the single pair of rollers 34.

What is claimed, is:—

1. In a separating machine, a flexible belt formed of a series of connected sections, a 90 drum for imparting a vibratory motion to the belt and including projecting members adapted to contact with the belt at the points thereof where the sections are connected, and means for adjusting said members to maintain the latter in contacting relation with such points of the belt irrespective of the shortening or lengthening of the belt.

2. In a separating machine, a belt formed of a series of interlooping strands, a drum 100 for imparting a vibratory motion to the belt including projecting members adapted to contact with the belt at the points where the strands interloop, and means for adjusting said members to maintain the latter in 105 contacting relation with the interlooping portions of the strands irrespective of variations in the length of the belt.

3. In a separating machine, a belt formed of a series of interlooping wire strands, one 110 terminal of each strand being provided with an eye to engage with the end loop of an adjacent strand, the opposite terminal of each strand being free from connection with the end loop of the adjacent strand, said 115 free end being turned inward, the construction being such that the assembled loops present substantially continuous edge portions, and guiding means adapted to be uniformly engaged by the substantially continuous edge portions of the belt.

4. In a separating machine, a sorting belt comprising a plurality of lengths of wire, each length being formed into a series of loops, the connecting portions of the loops 125 of one length of wire being engaged with the loops of the adjacent length of wire, the ends of each length of wire terminating near the adjacent length to produce substantially unbroken edges for the sorting belt.

5. In a sorting machine, the combination with a frame and drums mounted therein, of a sorting belt engaging with the drums and comprising a plurality of interwoven 15 lengths of wire, each formed into loops having parallel arms, the arms of the adjacent loops of each length lying one above the other, said wires at the ends of the arms being bent to form small connecting loops, 20 said small loops of one length being engaged centrally of the large loops of the next adjacent length, one end of each length of wire being engaged through a small loop of one adjacent length, and then carried away from said small loop to a point adjacent the terminal of the large loop of the other adjacent length, and then turned inwardly of the element, and guide devices carried by the frame for engagement with the edges of the belt.

In testimony whereof, I affix my signature, in the presence of two witnesses.

FRANK BOGGS.
